(57) **CLAIM**

The ornamental design for a fountain la tropea, as shown and described.

DESCRIPTION

FIG. 1 is a front perspective view for a fountain showing my new and original design;

FIG. 2 is a front elevation view thereof;

FIG. 3 is a back elevation view thereof;

FIG. 4 is a right side elevation, and a identical left side elevation view thereof; and,

FIG. 5 is a top view thereof.

View of the bottom side of the fountain has been omitted because such side is flat and devoid of surface ornamentation.
